(57) **CLAIM**

The ornamental design for an airbrush cam, as shown and described.

DESCRIPTION

FIG. 1 is a top and front perspective view of an airbrush cam showing my new design;

FIG. 2 is a front elevation view thereof;

FIG. 3 is a rear elevation thereof;

FIG. 4 is a right side elevation view thereof;

FIG. 5 is a left side elevation view thereof;

FIG. 6 is a top plan view thereof;

FIG. 7 is a bottom plan view thereof;

FIG. 8 is a bottom and rear perspective view thereof; and,

FIG. 9 is another right side elevation view thereof, showing the airbrush cam in an environment as part of an airbrush. The broken lines in FIG. 9 are for the purpose of illustrating environmental structure that forms no part of the claimed design.

1 Claim, 8 Drawing Sheets
